UNITED STATES PATENT OFFICE.

FERDINAND JOHNSON, OF TOLEDO, OHIO.

CAR-COUPING.

SPECIFICATION forming part of Letters Patent No. 252,775, dated January 24, 1882.

Application filed July 2, 1881. (No model.)

To all whom it may concern:

Be it known that I, FERDINAND JOHNSON, a citizen of the United States, residing at Toledo, in the county of Lucas and State of Ohio, have 5 invented new and useful Improvements in Car-Couplings, of which the following is a specification.

This invention relates to that class of car-couplings in which a swinging bail is employed 10 for the purpose of raising the link into position for coupling.

My invention consists essentially of a swinging bail pivoted to the draw-head or to the longitudinal car-sills by means of pins passing 15 through slots in the ends of the bail, whereby the bail can be raised in order to elevate the link into a horizontal position ready for coupling.

It further consists in forming said swinging 20 bail with a curve or recess at the upper edge of its front transverse bar for receiving the link, said bar being also provided at such point with a wedge-shaped abutment, the special construction and purposes of which will be hereinafter fully explained.

In the drawings, Figure 1 is a top or plan view of a car-coupling provided with my improved bail; Fig. 2 is an end view, and Fig. 3 a side elevation, of the same.

30 A indicates the draw-head, which is provided, as usual, with the rear slide-bar, a, that abuts against a spring, said draw-head being also formed with the bell-mouth recess for receiving the links, and with the vertical holes or 35 passages, through which the coupling-pin B is passed in order to engage the link and retain one end of the same in the draw-head. The slide-bar of the draw-head is arranged between the longitudinal sills or bars C C and under the 40 transverse sill D of the car. When the link E is engaged by the coupling-pin in a draw-head, as illustrated in Fig. 3, the link will drop into the inclined position indicated by dotted lines.

In order to raise the link to a horizontal 45 position, so that it will enter the draw-head of another car, I provide a swinging bail, F, which, when raised, will strike against the link and lift the same into position ready for coupling. This bail is formed with slots f f at its 50 ends, and is hung upon the sides of either the draw-head or the longitudinal sills by means of pins G passing through its said slotted

ends. This connection of the bail with the draw-head or sills admits of a backward-and-forward as well as a swinging movement on 55 the part of the bail. The transverse bar, constituting the front part of the bail, is curved or recessed at its top edge, so as to form a saddle for supporting and maintaining the link in line with the axis of the draw-head, and 60 hence guide the link into the draw-head of the next car.

To the sides of the draw-head or sills I secure stops H, which in the present instance consist each of a metal plate secured in place by 65 screws, and provided at its lower end with a stud having its top surface inclined for the bail to rest upon. The transverse front bar of the bail is formed along a portion of its length with an enlargement or downward projection, 70 g, which constitutes an abutment at the front of the bail. This abutment is made wedge-shaped in cross-section for the purpose presently explained, the large end of the wedge being at the lowest point, so that there will be 75 a gradual taper from the base of the abutment to the curved edge of the bail. This abutment extends downwardly at right angles to the bail, so that when it is jammed against the draw-head by an opposing draw-head it will lie 80 against the former draw-head, and thus not be broken or injured.

In coupling the cars I raise the front portion of the bail, so as to elevate the link to a horizontal position, ready for coupling. The 85 bail can be raised directly by hand, or by any suitably-arranged lever, or by means of a chain passing over a pulley at the top or side of the car and connected with a hand wheel or a pivoted lever. When the draw-heads of the 90 cars come together the link engaged by the coupling-pin of one draw-head and supported by the bail will be guided into the opposing draw-head, in which it can then be engaged by the coupling-pin belonging to such draw-head. 95 This draw-head, striking against the abutment of the bail, will force the latter back so that its abutment will strike against the face of the draw-head that is embraced by the bail, the slots in the latter admitting of such yielding 100 movement on the part of the bail. The increased thickness of the bail, which is due to the wedge-shaped abutment, not only prevents breakage of the bail at this point, but also,

when the cars move slightly apart, admits of the bail readily dropping down from between the draw-heads, the inclined sides of the abutment allowing the latter to clear the draw-heads. If the abutment were rectangular in cross-section, the cars would have to be brought farther apart to allow the bail to drop, since in falling it necessarily must swing in a curved path. When the bail thus swings down it will 10 also slide forward to the extent of the slots in its ends, the pins being at the rear ends of the slots when the bail rests upon the inclined surfaces of the stops. When raised from this position it will be seen that its bar will come 15 in front of the draw-head, and hence will not come in contact with the same until pushed back by an opposing draw-head.

Having thus described my invention, what I claim is—
20 1. The combination, in a car-coupling, of the

draw-head with the swinging bail, formed with an abutment, *g*, at the front and with rear slotted ends, said bail being pivoted by pins passing through its slots, and being arranged to elevate the link to a horizontal position, 25 ready for coupling, substantially as described.

2. The combination, in a car-coupling, of the draw-head with the pivoted bail formed at its front portion with the curved recess *f* for receiving the link, and with the wedge-shaped abutment *g*, projecting downwardly at right angles to the bail and having an upward taper, substantially as described.

In testimony whereof I have hereunto set my hand in the presence of two subscribing witnesses.

FERDINAND JOHNSON.
